UNITED STATES PATENT OFFICE.

THOMAS C. BUSBEE, OF ANDALUSIA, ALABAMA, ASSIGNOR OF ONE-HALF TO ANDER J. BUSBEE, OF ANDALUSIA, ALABAMA.

SUBSOILER.

1,157,295.

Specification of Letters Patent. Patented Oct. 19, 1915.

Application filed July 31, 1915. Serial No. 42,937.

To all whom it may concern:

Be it known that I, THOMAS C. BUSBEE, a citizen of the United States, residing at Andalusia, in the county of Covington and State of Alabama, have invented certain new and useful Improvements in Subsoilers, of which the following is a specification, reference being had to the accompanying drawings.

10 This invention relates to certain improvements in subsoilers, and it is an object of the invention to provide a novel and improved device of this general character which may be applied with facility and convenience to the stock of a plow and which may be adjusted vertically in order to meet the varying requirements of practice.

15 The invention consists in the details of construction and in the combination and arrangement of the several parts of my improved subsoiler whereby certain important advantages are attained and the device is rendered simpler, less expensive and otherwise more convenient and advantageous for use, all as will be hereinafter more fully set forth.

The novel features of the invention will be carefully defined in the appended claims.

20 In order that my invention may be the better understood, I will now proceed to describe the same with reference to the accompanying drawings, wherein—

25 Figure 1 is a view in side elevation of a subsoiler constructed in accordance with an embodiment of my invention and in applied position; Fig. 2 is a sectional view taken substantially on the line 2—2 of Fig. 1; and Fig. 3 is a fragmentary view in perspective of the connecting end of the subsoiler B as herein set forth.

30 As disclosed in the accompanying drawings, 1 denotes a plow stock of conventional construction, herein disclosed as integrally produced with the beam 2 and projecting rearwardly from the stock are the handle members 3 tied or connected intermediate their lengths by the cross rod 4.

35 5 denotes the stock of the subsoiler attachment disposed on a suitable curvature 50 and having one extremity bifurcated or

forked, as at 6, to straddle the stock 1 and pivotally engaged with said stock through the medium of the removable pin 7. The stock 6 has pivotally engaged therewith the bracing strips 8 having their upper or free 55 extremities provided with the longitudinal notches 9 whereby the bracing strips may be adjustably engaged with the inwardly disposed projections 10 carried by the handles 3 in order to maintain the subsoiler in 60 its various vertical adjustments, said projections being preferably bolts provided with hinged heads and in threaded engagement with the handles 3 whereby said bracing strips 8 may be effectively clamped and 65 maintained in their varying adjustments.

From the foregoing description, it is thought to be obvious that a subsoiler constructed in accordance with my invention is of an extremely simple and comparatively 70 inexpensive nature and is particularly well adapted for use by reason of the convenience and facility with which it may be assembled, and it will also be obvious that my invention is susceptible of some change and 75 modification without material departure from the principles and spirit thereof and for this reason I do not wish to be understood as limiting myself to the precise arrangement and formation of the several 80 parts herein shown in carrying out my invention in practice.

I claim:

35 In combination with a plow beam provided with handles, a subsoiler stock pivotally engaged with the beam, bracing strips 85 pivotally engaged with the subsoiler stock and provided with longitudinally spaced recesses, and endwise adjustable headed members carried by the handles of the plow beam 90 with which the bracing strips are adapted to engage, said headed members being capable of adjustment to clamp the strips against displacement.

40 In testimony whereof I hereunto affix my 95 signature in the presence of two witnesses.

THOMAS C. BUSBEE.

Witnesses:

H. HILLE DONGOLD,
J. D. STRIBLING.
